UNITED STATES PATENT OFFICE.

HENRY CLAY BASCOM AND TOBIAS S. HEISTER, OF LANSINGBURG, ASSIGNEES TO THE CO-OPERATIVE FOUNDRY COMPANY, OF ROCHESTER, NEW YORK.

DESIGN FOR A HEATING-STOVE.

SPECIFICATION forming part of Design No. 19,483, dated December 17, 1889.

Application filed August 20, 1889. Serial No. 321,408. Term of patent 7 years.

To all whom it may concern:

Be it known that we, HENRY CLAY BASCOM and TOBIAS S. HEISTER, citizens of the United States, residing at the village of Lansingburg, county of Rensselaer, and State of New York, have invented and produced a new and original Design for Stoves, of which the following is a specification, reference being had to the accompanying drawing, forming a part thereof, and consisting of a single figure affording a view in perspective of our newly-designed stove.

Our new design embodies a plurality of constituent elements or members, comprising ornaments peculiar to those parts of a stove known as the leg-base, bottom, ash-pit section, foot-rail, foot-rail bracket, doors, top, and dome or cover.

We embody our design in a heating-stove having an approximately-rectangular shape in cross-section through its various horizontal planes, the main part or body being, however, more rounded by preference than the other parts; and the invention consists, as a whole, in the conformation and ornamentation substantially as illustrated, and herein-after described and pointed out.

The leg-base A, having the legs A' depending from the corners A², is provided with side ornaments consisting of two curved ridges or ribs A³, each extending from a base corner to a central scroll and shell cluster A⁴, and provided with scroll terminals and a plurality of small scrolls A⁵ and stems A⁶, projecting laterally from such ribs. The lower edges of bottom B, the upper edges of ash-pit A⁷, and the lower edges of top F are provided with an ornamental border B', consisting of a horizontal row of heavy beading on the several sides of the stove, the individual beads B² being arched on their upper ends and terminating at their lower ends in a horizontal rib or ridge B³. The bottom is also provided with two vine-like ribs B⁴ and B⁵, apparently intertwined and running along the sides of the bottom sections in opposite directions, with numerous scroll branches B⁶. The doors C are each provided with a rope border C' and a central ornament consisting of intersecting curved figures C², having scroll terminals C³, a common central point of inter-

section, and a rosette C⁴, located at such point of intersection. Projecting from two opposite sides of the ash-pit are foot-rail brackets in the form of a large scroll C⁵, having smaller scrolls and stems branching therefrom. The foot-rail C⁶ is provided with a central ornament consisting of a scroll and shell cluster C⁷ between two half-shells C⁸, also with end ornaments consisting of the rosettes C⁹. The two illuminating-sections D' and D² are separated by an ornamental band D, running horizontally from one side of the stove to another. The band, as seen on the several sides of the stoves, has a rosette near the vertical edges of such sides and a third rosette located centrally of the band and the sides of the stove, the space in the band between the edge rosettes and the central rosette being occupied by ornamental leaf-like figures, and the upper illuminating-section D³ is separated by a similar band D⁸ from the nickel or tile section E. The ornamented convexed top F is separated from the tile-section by the ornamented concave cornice E'. Rising from the top is a dome or cover H, ornamented by a horizontal row or band of beading, consisting of a series of equidistant broad beads H', separated from each other by a space about equal to the breadth of the individual beads and having their upper ends H² arched or convexed, the spaces intervening between such beads being filled by a series of similarly-arched narrow beads H³. The dome is also provided with a horizontal row of leaf ornaments H⁴ just above the row of beading.

Having thus described our new design, what we desire to claim and secure by Letters Patent is—

1. The design for a stove, consisting of the ornamentation of the several stove-sections, including the curved ribs, arched beads, and vine-like ribs, the rope-like border inclosing intersecting curves, the scroll form for the bracket, the rosettes and leaf-like ornaments for the band, and the series of arched beads and leaf-like ornaments, substantially as described and shown.

2. In a design for a stove, the design for the leg-base, consisting of the curved ribs, scroll and shell cluster, and scroll terminals, substantially as described and shown.

3. In a design for a stove, the design for the bottom, consisting of the arched beads arranged upon a rib and the intertwined vine-like ribs having scroll branches, substantially as described and shown.
4. In a design for a stove, the design for a stove-door, consisting of the rope-like border and the central ornament having intersecting curves terminating in scrolls, and the rosette at the intersection of the curves, substantially as described and shown.
5. In a design for a stove, the design for the foot-rail, consisting of the scroll-like bracket, supports, and the ornament for the rail, consisting of the central scroll-like cluster, the half-shells, and the terminal rosettes, substantially as described and shown.
6. In a design for a stove, the design for a band separating two sections, consisting of a central and terminal edge rosettes on each side of the stove and a leaf-like ornament between the central and edge rosettes, substantially as described and shown.
7. In a design for a stove, the design for a cover, consisting of the series of broad arched beads below the series of leaf-like ornaments, substantially as described and shown.

In testimony whereof we have hereunto set our hands this 13th day of August, 1889.

HENRY CLAY BASCOM.
TOBIAS S. HEISTER.
